DESCRIPTION

FIG. 1 is a front view of an X-ray generating apparatus of the present invention;

FIG. 2 is a rear view thereof;

FIG. 3 is a top view thereof;

FIG. 4 is a bottom view thereof;

FIG. 5 is a right view thereof;

FIG. 6 is a left view thereof;

FIG. 7 is a perspective view thereof; and,

FIG. 8 is an enlarged view showing a portion of FIG. 5 defined by lines 8-8 and 8'-8'.

The features shown in evenly-dashed broken lines depict environmental subject matter only and form no part of the claimed design. The dot-dash broken lines in the drawings represent the bounds of the claimed subject matter, the dot-dash broken lines, themselves forming no part thereof.
